[57] CLAIM

The ornamental design for a contact lens sterilizer unit,
substantially as shown and described.

DESCRIPTION

[21] Appl. No.: 889,826

FIG. 1 is a perspective view of our contact lens sterilizer unit taken generally from the front thereof;
FIG. 2 is a front elevational view of the sterilizer unit of FIG. 1, with a lens case of the type to be accommodated by said unit shown in dotted outline for illustrative purposes only;
FIG. 3 is a right side elevational view thereof;
FIG. 4 is a left side elevational view thereof;
FIG. 5 is a rear elevational view thereof; and
FIG. 6 is a top plan view thereof.
